(57) **CLAIM**

I claim the ornamental design for a gel nail UV curing light with stamper, as shown and described.

DESCRIPTION

FIG. 1 is a top perspective view of the gel nail UV curing light with stamper showing my new design;

FIG. 2 is a bottom perspective view thereof;

FIG. 3 is a front elevational view thereof;

FIG. 4 is a right hand side elevational view thereof;

FIG. 5 is a rear elevational view thereof;

FIG. 6 is a left hand side elevational view thereof;

FIG. 7 is an enlarged top view thereof; and

FIG. 8 is an enlarged bottom view thereof.

FIG. 9 is a top perspective and partially exploded view thereof; and,

FIG. 10 is a bottom perspective and partially exploded view thereof.

The broken lines in the figures are for the purpose of illustrating portions of the gel nail UV curing light with stamper, which form no part of the claimed design.

1 Claim, 9 Drawing Sheets
